UNITED STATES PATENT OFFICE.

WILLIAM FREDERICK FEDOSENKO, OF PERDUE, SASKATCHEWAN, CANADA.

HOSPITAL INVALID BED.

Application filed November 27, 1923. Serial No. 677,252.

To all whom it may concern:

Be it known that I, WILLIAM FREDERICK FEDOSENKO, a subject of the King of Great Britain, of the postal district of Perdue, in the Province of Saskatchewan, Canada, having invented new and useful Improvements in Hospital Invalid Beds, do hereby declare that the following is a full, clear, and exact description of the same.

10 My invention relates to improvements of an invalid support primarily designed for use in connection with hospital bed, using a spring mattress in two sections, the upper or head portion of which rests on a movable frame, whereby a patient can be easily elevated to a sitting position and lowered to a reclining position without discomfort, and which can be easily operated by an attendant or by the patient himself.

20 I attain these objects by the mechanism illustrated in the accompanying drawings in which:

Figure 1 is a side view of the mechanism;

Figure 2 is a vertical section in the plane 25 of the quadrant;

Figure 3 is a top view of the mechanism showing its connection with the frame of the bed;

Figure 4 is an end view of the mechanism 30 in elevation;

Figure 5 is a plan of the wheel member and attachments.

Similar letters refer to similar parts throughout the several views.

35 10 is the existing frame of a hospital bed to which is attached a movable frame "b" hinged so as to rotate in the sockets 12 which are attached to the frame of the bed. The frame 11 carries the movable section of the 40 spring mattress which is intended to simply rest on it (the mattress is not shown in the drawings).

A cross bar 13 extends across the framework of the bed from side to side and is 45 suspended from same as indicated in Fig. 4. This cross bar carries the weight of the mechanism which is bolted to it. Suspended from the cross bar 13 is a frame 14 and bracket 15 supporting a shaft 16 which extends outwards a little beyond the frame

of the bed. To this end of the shaft and loosely pivoted thereto is a lever arm 17, having at its outer end a handle 18 pivoted to the lever arm 17 by the rivet 19. This handle is capable of revolving about the 55 pivot 19. Attached to the cross arm 20 of the handle 18 at either end are connecting wires or rods 21 operating the pawls 22 which engage the ratchet wheels 23, one on either side of the lever arm 17 and which are firmly attached to the shaft 16. This arrangement provides a means of rotating the shaft 16 in either direction, at the will of the operator, by manipulation of the handle 18. The ratchet wheels 23 being 60 opposed to one another, the reciprocating motion of the handle 18 provides that when one ratchet wheel is engaged by the pawl operating in conjunction with it, the pawl 65 operating in conjunction with the other ratchet wheel is released, the stops 17^a on the frame 10 retain the lever 17 in the position indicated in Figure 1. At the inner end of the shaft 16 and between the two arms of the frame 14 is a toothed wheel 24 which 70 is attached firmly to the shaft 16 and which engages with the upper edge of the quadrant 25. The upper edge of the quadrant is toothed to correspond to and fit into the wheel 24. The quadrant rests upon the 75 lower edge of the frame 14 upon which it is free to slide. The arm 26 of the quadrant 25 is pivoted at its upper end on the cross bar 27 of the frame 11.

80 A rotary motion of the shaft 16 by operation of the lever arm 17 causes the wheel 24 to revolve and by means of its connection with the toothed edge of the quadrant produces a longitudinal motion in the quadrant which is transmitted to the frame 11 by means of its pivoted connection to the bar 27. A rotary motion of the shaft 16 thus 85 raises or lowers the frame 11 by causing it to revolve in the sockets 12. The amount of the elevation of the frame 11 is regulated by the amount of the rotary motion conveyed to the shaft 16 through the lever arm 17 by the operator and is thus at all times 90 under his control.

95 In addition to the force imparted to the 100

frame 11 by means of the quadrant 25 the shaft 16 and the lever 17, and supplementary thereto I provide a coiled spring 28 which assists in the elevation of the frame 11. The spring 28 is coiled about a shaft 29 and is supported by frame 30 which is suspended from the cross bar 13 and bolted to it. One end of the coiled spring 28 is attached to the frame 30 and the other end to the shaft 29. A lever arm 31 is loosely mounted on the shaft 29 and attached thereto at the lower end is a pawl which engages the ratchet wheel 32 the lever arm being held in almost vertical position by the stop 31^a. A wheel 33 rotates loosely on the shaft 29 and is connected therewith by means of a pawl attached to the wheel 33 which engages the ratchet wheel 34 which is firmly attached to the shaft 29.

20 A rotary motion of the shaft 29 produces a tension in the coiled spring 28 and this is imparted to the wheel 33 by means of the ratchet wheel 34 and pawl attached to the wheel. The amount of tension can be regulated by the operator to suit the weight of the various patients who may use the bed.

25 Firmly attached to the outer edge of the wheel 33 is a bar 35 whose outer end is slotted and pivoted to the bar 36 at its lower end. The upper end of the bar 36 is pivoted to the cross bar 27 of the frame 11. The wheel 33 is provided with a stop 33^a which engages with the frame 30, this stop being so set on the circumference of the wheel that 30 after revolving a certain distance under tension of the coiled spring 28, the rotary motion of the wheel 33 comes to an end and the tension in the spring ceases to exert any force through the bars 35 and 36. This provision is made to assist in raising the frame 11 upon which a patient is reclining on a mattress, from a horizontal position to an inclined position, more force being required 35 in this portion of the operation than when the frame 11 has reached a position approaching the perpendicular. When the frame has been elevated by means of the force applied by the patient or an attendant, 40 by rotating the lever arm 17, together with the force exerted by the coiled spring to a certain predetermined inclination, the stop 33^a on the circumference of the wheel 33 engages on the frame 30. Any further inclination or elevation of the frame 11 must necessarily be produced by the operation of the quadrant 25 by exerting a force on the lever bar 17, this latter increase in elevation being entirely under the control of the attendant or patient, and danger of any sudden or unintentional elevation of the frame, liable to throw the patient too far forward 45 due to the action of the coiled spring, is thereby eliminated. The slot in the outer end of the bar 35 permits of the additional elevation of the frame 11 by means of the

lever arm 17 as thus described after the coiled spring has ceased to exert an upward thrust by reason of the stop 33^a aforesaid attached to the wheel 33 having come into a position to engage the frame 30.

50 In lowering a patient from an upright to a horizontal position the operation above described is reversed. The patient or attendant works the lever arm 17 after reversing the direction of motion thereby applied to the shaft 16 by means of the handle 18 releasing the pawl 22 previously engaged with the ratchet wheel 23 and engaging the pawl in the opposing ratchet wheel 23. The shaft 16 and the toothed wheel 24 is thus 55 rotated and the frame 11 is lowered by means of the quadrant 25 and arm 26 until the frame 11 reclines sufficiently to bear upon the coiled spring 28. On a still further rotation of the shaft 16 by means of the lever bar 17 a portion of the weight of the frame 11 is shifted to and is carried by the coiled spring 28 in such a manner as to complete the operation of lowering the patient 60 to a horizontal position without jar or shock.

65 What I claim as my invention is:

1. In a device of the character described, a bed frame, a second frame operatively mounted therein and means for raising and lowering said frame comprising a suitably formed quadrant, a shaft provided with means designed to engage with the quadrant, said quadrant being pivotally connected to the second frame whereby on the shaft being operated the quadrant is moved forwards or backwards to raise or lower said frame, supplementary raising and lowering means for the second frame comprising a spring-actuated countershaft, a wheel 70 loosely mounted on the shaft provided with a pawl, and a ratchet wheel fixedly mounted on the shaft and adapted to be engaged by said pawl, a lever arm pivotally connected through a link with the second frame at one end and fixedly connected to said wheel at the other end.

75 100 105 110 115 120 125 130

2. An adjustable bed of the character described comprising a main frame and an operatively mounted second frame, a quadrant pivotally connected to the second frame, a shaft provided with means adapted to engage with said quadrant and pawl and ratchet wheel means, in combination with a rotatable handle flexibly connected to said pawl and ratchet wheel for operating said shaft, auxiliary raising and lowering means for the second frame comprising a second shaft operatively connected to the second frame a shaft arm and a spring for operating said shaft and stop means for said spring.

3. In a bed of the character described a main frame, an inner frame pivotally mounted on the main frame, a quadrant operatively connected to the inner frame, a shaft

provided with means adapted to engage with said quadrant, means for operating the shaft from a distance to move the quadrant backwards and forwards, to raise or lower the 5 inner frame, and auxiliary raising and lowering means for the inner frame comprising a spring actuated counter shaft, a lever arm

for the shaft and means for operating said arm and stop means for said operating means. 10

In witness whereof I have hereunto set my hand.

WILLIAM FREDERICK FEDOSENKO.
